UNITED STATES PATENT OFFICE.

ALEXANDER BARRIE, OF NEW YORK, N. Y., ASSIGNOR TO THE COURT
PERFUMERY COMPANY, OF SAME PLACE.

DESIGN FOR A BOTTLE.

SPECIFICATION forming part of Design No. 29,126, dated August 2, 1898.

Application filed July 6, 1898. Serial No. 685,284. Term of patent 7 years.

To all whom it may concern:

Be it known that I, ALEXANDER BARRIE, a citizen of the United States, residing at New York, in the county and State of New York, have invented and produced a new and original Design for a Bottle, of which the following is a specification, reference being had to the accompanying drawings, forming part thereof, in which—

10. Figure 1 is a side elevation; Fig. 2, an end elevation, and Fig. 3 a section at the line xx of Fig. 1.

The leading features of my design for a bottle consist of the short body of flattened hexagonal configuration tapering toward the base of the bottle and rounded at the respective ends, the hexagonal base, the hexagonal shoulders, the neck, and the annular rib at

the base of the neck. The short body A is of flattened hexagonal configuration, (see Fig. 20 3,) the respective faces a of the hexagon being slightly convex and tapering toward the base of the bottle, with the ends rounded at a' at the lower edge to the hexagonal base b and rounded at the upper end at a^2 to the 25 hexagonal shoulders c . The neck d has an annular rib e near its junction with the hexagonal shoulders c .

What I claim is—

The design for a bottle, substantially as 30 shown and described.

Signed by me this 1st day of July, 1898.
ALEXANDER BARRIE.
